UNITED STATES PATENT OFFICE.

OREN F. BALTZLEY, OF HAGERSTOWN, MARYLAND.

DISPLAY MACHINE.

1,409,517.

Specification of Letters Patent. Patented Mar. 14, 1922.

Application filed September 25, 1920. Serial No. 412,661.

To all whom it may concern:

Be it known that I, OREN F. BALTZLEY, a citizen of the United States, residing at Hagerstown, in the county of Washington and State of Maryland, have invented a certain new and useful Improvement in Display Machines, of which the following is a full, clear, and exact description.

The object of this invention is to provide a machine for displaying or exhibiting signs, advertisements, pictures and other objects in succession and in a substantially automatic manner, in such way that a single person or a number of persons may use the machine for display or exhibition purposes either as owner or lessee or space renter.

The invention consists of a frame having a storage rack on which are movably mounted any number of display frames containing signs, advertisements, pictures or other objects, and a vertically reciprocating carriage, combined with transferring mechanisms, parts of which are elements of the carriage and the remainder coordinated with its movements, by which a display frame is taken from the storage rack and moved to a transfer rack from which it is moved into position to be displayed or exhibited for a predetermined time, and thereafter displaced and carried to the opposite end of the rack so as to be in position to be exhibited or displayed again when other display frames on the rack have been taken one by one and moved into displaying or exhibiting position, as I will proceed now to explain and finally claim.

In the accompanying drawings illustrating the invention, in the several figures of which like parts are similarly designated, Figure 1 is a front elevation of the machine without the casing that may be employed to enclose it. Fig. 2 is a rear elevation, the motor being omitted. Fig. 3 is a side elevation. Fig. 4 is a substantially vertical central section, with parts broken away to more fully show the carriage member. Fig. 5 is a top plan view. Fig. 6 is a longitudinal section, on a larger scale, showing part of the operating mechanism. Fig. 7 is a perspective view of the upper front portion of the frame, showing a portion of the transfer mechanism. Fig. 8 is a perspective view of the front corner or angle of the upper portion of the carriage. Fig. 9 is a perspective view of the corner or angle of the

rear portion of the carriage, both Figs. 8 and 9 showing portions of the transfer mechanism. Fig. 10 is a perspective view of the carriage members, detached, with two display frames thereon shown in dotted lines and portions of the uprights of the frame also shown in dotted lines. Fig. 11 is an elevation and partial section of the escapement disk for operating the carriage. Fig. 12 is an elevation of the wiper cam and crank arm for controlling the movement of the rock levers for shifting the display frames on the storage rack. Fig. 13 is an elevation of the notched cam, with its crank arm partly in section, for preventing overthrow of the main shaft. Fig. 14 is an elevation of the scroll cam with its crank arm for controlling the effective movement of the rock shaft. Fig. 15 is an elevation of the cam and its crank arm for controlling the movement of the rock levers for shifting the display frames from the rear to the front of the machine on the transfer rack for display purposes.

A base 1 is provided upon which are rigidly erected the uprights 2 and 3, and these uprights are provided at their upper ends with similar right and left cross-pieces 4 and 5, L shaped in cross-section, which are connected by tie-rods or bolts 6 and 7, and 80 constitute the transfer rack herein referred to. About the center of the uprights are fixed the right and left pieces 8 and 9, also L shaped in cross-section, and jointly forming a storage rack for supporting in a pendant way the display frames 10, said frames having at their upper ends the laterally projecting trunnions 11 which engage the rack members. These frames receive the thing to be exhibited or displayed, such as 95 an advertisement, sign, picture, or other object. These rack members 8 and 9 are arranged on the inner sides of the uprights.

A frame-transferring carriage 12, shown detached in Fig. 10, is mounted to travel up 100 and down the uprights, and consists of like cross-pieces 13 fixed to and carried by downwardly extending slides 14, arranged parallel with the uprights, all mounted upon the outside of the uprights. Said slides 14 105 have flanged connectors 15 and 15^x at their upper and lower ends respectively to embrace the uprights and connect the carriage in a sliding manner to said uprights. By this construction the carriage is free to move 110

past the storage rack, in both its up and its down travel. The cross-pieces 13 of the carriage have their rear ends 16 extended toward one another, and these ends are provided with inwardly projecting hooks 17 adapted to take the display frames one by one from the rack and move them into position to be engaged by the transfer and display elements hereinafter described, said frames being restrained from lateral escape from said hooks by means of the stops 18 on the ends 16. Likewise these cross-pieces 13 have their front ends 19 extended toward one another, and such extensions are provided with the outwardly extending projections 20 and the adjacent inwardly extending projections 21, said ends 19 being cut away above these projections. Hooks 22 are arranged on the edges of the cut-away portions and extend inwardly and point upwardly. Next to the hooks are the projections 23 which also extend inwardly and serve as stops to prevent the lateral dislocation of the display frames, as they are taken from the display mechanism by the carriage and returned to the rack.

The base 1 is provided with bearings 24, 25 and 26, in which is supported a shaft 27, having the cranks 28 to which are pinned the lower ends of rods 29, the upper ends of said rods being pinned to the carriage slides 14 by means of which the carriage is given a vertical reciprocation on the uprights 2 and 3 to effect the removal of the display frames one by one from the storage rack to the transfer rack. Motion may be imparted to the shaft 27 by any suitable means, and as herein shown, these means comprise an electric motor 30—see Fig. 5—, having a shaft 31 on which is a worm 32 which engages a worm-wheel 33 which is keyed to a sleeve 34 loosely mounted on the shaft 27. Fixed to this sleeve is a disk 35 having a peripheral notch 36 and a laterally projecting pin 37, and fixed to the shaft 27 is an arm 38 which carries an L-shaped latch 39 normally pressed toward the disk 35 by a spring 40, so as to engage the notch 36 in said disk. This latch is normally pressed away from the disk by means of a latch lever 41 pivoted on an extension 42 of the bracket 25 and held down by a spring 43 and having one corner 44 beveled. This latch lever has a depending arm 45 on which is axially mounted a star-wheel, 46, herein-after termed the timing-wheel, and having any desired number of notches 47 of equal depth and one or more notches 48 of less depth, said timing-wheel being so arranged relatively to the disk 35 as to turn in the path of movement of the pin 37 on said disk. As will be observed, the motor turns the worm-wheel 33 and consequently the sleeve 34 and the disk 35 continuously without turning the shaft 27. In the rotation of the

disk 35 its pin 37 will engage and turn the timing-wheel on its axis without affecting the latch lever, but when the timing-wheel has been turned so as to bring the shallow notch 48 into engagement with the pin 37 then by reason of the fact that said notch is shorter than the notches 47, the timing-wheel will be lifted and thereby raise the latch lever so that it will release the latch and permit its spring 40 to force it down into engagement with the notch in the disk 35 and thereby couple the shaft 27 with the sleeve 34 and the worm-gearing and cause said shaft to turn. This turning of the shaft causes it to operate the crank arms 28 and effect first the complete upward and then the complete downward movement of the carriage on the uprights 2. At the completion of this movement the pin 37 will engage one of the longer notches of the timing-wheel and the latch lever will be drawn toward the latch and its beveled end 44 will engage the upright portion of said latch and lift it out of contact with the notch in the disk and thereby uncouple the arm 38 and again permit the disk to run free with its sleeve 34 on the shaft 27 without turning said shaft. The timing-wheel and its cooperative adjuncts constitute a sort of escapement.

As the carriage rises its hooks 17 will engage the trunnions 11 of the display frame 10 at the rear of the machine and carry up said frame inside of the pendant projections 49 of the transfer rack back of the latches 50 which are pivoted to lugs 51 depending from said rack and are held in engaging position by springs 52. During the upward movement of the carriage the rock levers 53 pivoted at 54 to the uprights have been moved over to the back of the machine, as indicated by dotted lines in Fig. 3, so as to be in position to engage the trunnions of the display frame thus elevated, and thereafter these levers 53 are moved toward the front of the machine and carry the display frame on the ledges 55 of the transfer rack toward the front of the machine and underneath the guards 56 and into contact with cam levers 57 pivoted at 58 to lugs 59 on the transfer rack and held elevated by the spring 60, so that their cam-surfaces 61 will be in the path of movement of the trunnions. These levers 57 have the off-set ends 62 provided with notches 63 to engage projections 64 on trip levers 65, which are pivoted to lugs 66 depending from the transfer rack and connected by the springs 60 with the levers 57 so as to draw them away from said levers when released by the depression of said levers occasioned by the crossing of the trunnions of the moving display frame over said levers 57. The tripping of the levers 65 is effected by the inwardly extending projections 21 of the carriage as they come oppo-

site, and when so tripped they release the displayed frame and are held set by the levers 57. The previously positioned display frame has been supported in such display 5 position against the pendant projection 49^x, Figs. 1, 3, 4 and 7, by means of the surfaces 67 of levers 65 and therefore as the said previously exhibited display frame is released, it falls upon the hooks 22, and then 10 upon the descent of the carriage it is carried to the level of the storage rack and deposited upon the lugs 68 of rock levers 69 which transfer it to the storage rack and thereafter in their rearward movement, move the frame 15 up against the series of frames on said rack so as to be in position to be again displayed or exhibited in turn. In the movement of the carriage and the consequent movement of the rock levers 69, the tips 70 of said rock 20 levers come beneath lugs 71 on the shutter 72, but in the previously described movement of these rock levers to move the previously displayed frame to the rear, said rock levers escape from beneath these lugs 25 71 and release the shutter so that it drops to the bottom of the machine and thus permits the display or exhibition of the frame that had been moved into display or exhibiting position. The thus dropped shutter has 30 its lugs 73 extended sufficiently far to come into contact with the projections 20 on the carriage so as to be in position to be raised to cover the exhibiting opening at the next upward movement of the carriage.

35 The shutter has the lugs 73 at its upper end which are connected to endless belts 74 running over upper pulleys 75 and lower pulleys 76 on the machine frame, and provided with counterweights 77 so as to guide 40 and regulate the movement of the shutter. Tension springs 77^x may be interposed in the belts, or, as shown, may connect the belts and their counterweights. The bottom of the shutter when the parts are in display position 45 may rest upon buffers 78 of any suitable construction, here shown as rubber buffers, mounted on pins 79, erected on the extensions 80 of the brackets 81 which are secured to the uprights 2 and 3. Any suitable buffers may be used for this purpose. 50 On these extensions are also mounted rods 82 secured at their tops on extensions 83 of the transfer rack and the lugs 71 and 73 of the shutter are provided with holes 55 through which these rods extend, so that the said rods serve as guides or ways for the movements of the shutter.

I have thus described the general operation of taking a display frame from the 60 storage rack, carrying it up to the top of the machine frame and moving it across the transfer rack into display position while the display opening is covered with the shutter, then dropping the shutter so as to display 65 the frame that has been put into display or

exhibiting position, and then closing the display opening by raising the shutter, and displacing the displayed frame while another display frame is brought into position for display, and will now proceed to describe 70 the mechanism for controlling the transfer means. A rock shaft 84 is mounted in the brackets 81, and has fast on it the rock levers 69. On this rock shaft is fixed a crank arm 85 projecting toward the shaft 27 and carrying 75 a roller 86 in contact with a wiper cam 87 fast to shaft 27. Near the opposite end of the shaft 84 is a crank arm 88 loosely mounted on said shaft and provided at its opposite end with a tension spring 89 and with 80 a grooved roller 90, the latter engaging a cam 91 fast on shaft 27, said crank arm by its engagement with a notch 92 in the cam 91, serving to hold said shaft against turning when the crank arms 28 reach the bottom of 85 their throw; that is to say when they reach the dead center, thus obviating any overthrow by momentum or otherwise.

On the rock shaft 84 also is fixed a crank arm 93 carrying at its free end a spring- 90 pressed roller 94 in periodical rolling contact with the periphery of a scroll cam 95 fast to the sleeve 34. This scroll cam has a laterally deflected portion 96 between its high and low points. Upon the rotation of shaft 27, 95 cam 87, (by means of roller 86, crank arm 85, rock shaft 84 and crank arm 93), lifts the spring-pressed roller 94, at which time said roller 94 slides over into the path of scroll cam 95 where said roller 94 is permitted to 100 ride down on the periphery of cam 95 by reason of the high part of wiper cam 87 passing from beneath roller 86. Upon the arrival of roller 94 at the low point of cam 95, the laterally deflected portion 96 contacts with the side of roller 94 forcing said roller over and keeping it out of the path of the periphery of cam 95 until said roller is again raised by the means described.

It will be observed that wiper cam 87 is 110 stationary while the roller 94 is riding down on cam 95 and allowing rock levers 69 by means of springs 105 to release shutter 72 and move a display frame to the rear of the storage rack.

The brackets 81 are provided with bearings 97 in which is supported a shaft 98, and on this shaft is a crank arm 99 having a roller 100 at its free end and held by a spring 101 against the periphery of a cam 102 fast on 120 shaft 27. Fixed to the outer ends of the shaft 98 are crank arms 103 which are connected by rods 104 with the rock levers 53 that shift the display frames from the rear to the front of the machine.

The rock levers 69 when released from cam pressure are drawn by springs 105 toward the series of display frames on the storage rack and consequently these frames are forced toward the rear of the machine 130

so as to always have the outermost one in such position that its trunnions will be engaged by the hooks 17 of the carriage so that the frame may be raised to the transfer 5 rack at the next ascent of the carriage. During the period when the springs 105 are exerting their pressure upon the rock levers 69 as just described, the cams 87 and 95 are idle with relation to the crank arms 85 10 and 93 respectively, but when the timing wheel 46 has been turned to present its shallow notch 48 to the pin 37 on the disk 35 to couple the sleeve 34 and shaft 27 and cause them to turn jointly, then these cams become 15 operative with relation to their crank arms and the cam 87 acting upon its crank arm 85 so turns the shaft 84 as to move the rock levers 69 toward the front of the machine so as to be in position to support the shutter in its elevated position and to present its lugs 68 in position to receive the trunnions of the frame that has been on display. This movement of the rock shaft 84 lifts the crank arm 93 and holds it out of engagement 20 with its cam 95 until upon the descent of the carriage the high point of cam 95 comes into contact with the said crank arm, and at this time the high point of cam 87 is uppermost and when this high point of cam 87 25 leaves its crank arm 85 the cam 95 and crank arm 93 support the moving transfer parts while the carriage is at the bottom and then as the cam turns the rock shaft 84 is rocked so as to move the levers 69 toward the rear 30 of the machine, thus releasing the shutter and carrying the previously displayed frame to the rear of the rack. Meanwhile the crank arm 85 is being moved toward the low point of its cam as is also the crank arm 93 being 35 lowered to the low point of its cam, and when this last is reached, then the deflector element 96 of cam 95 throws the crank arm out of engagement with the cam and allows the springs 105 to hold the rock levers 69 40 against the series of display frames on the storage rack. Meanwhile the sleeve 34 and shaft 27 have been uncoupled and shaft 27 45 and the cams thereon are idle.

Thus it will be seen that the carriage performs no other functions than raising a frame into position to be displayed, raising the shutter to cover the display opening, and releasing and lowering a displayed frame for transfer back to the storage rack. The other operations are performed by positively actuated transfer mechanism, all under control of a single operating mechanism, as explained.

106 is a trough containing a lubricant 50 in which the worm-wheel 33 turns.

As already sufficiently indicated, the mechanism described is designed to be enclosed in a suitable casing having an opening covered by the shutter while the display 55 frame is being moved into display position

and from which the shutter is dropped so as to uncover and expose the display frame for a predetermined period, or in other words, until the sleeve 34 has turned a predetermined number of times to turn the timing 70 wheel so as to bring its shallow notch into cooperative relation with the pin 37 on the disk 35 to couple the sleeve and the shaft 27 so as to give the carriage its ascending movement. The signs or other objects in the 75 display frames may be of transparent or translucent material adapted to be illuminated in any suitable way, as by means of a light arranged within the casing.

The display machine is designed for use in 80 public places, either out of doors or indoors, and to be sold outright to exhibitors, or leased, or, especially when arranged out of doors in public places, to have space therein 85 rented to a number of exhibitors.

Variations in the details of construction and in the arrangement of parts are permissible within the principle of the invention as herein explained and hereinafter claimed.

What I claim is:

1. A display machine, having a storage rack adapted to receive a number of display frames, a transfer rack at a different altitude to receive such frames one by one from the storage rack, a vertically reciprocating carriage provided with means to take the frames one by one from the storage rack and move them to the transfer rack, and positively actuated means to transfer the frame on said transfer rack from the rear 100 of the machine to the front and to place it in display or exhibiting position.

2. A display machine, having a storage rack adapted to receive a number of display frames, a transfer rack at a different altitude to receive such frames one by one from the storage rack, a vertically reciprocating carriage provided with means to take the frames one by one from the storage rack and move them to the transfer rack, positively actuated means to transfer the frame on said transfer rack from the rear of the machine to the front and to place it in display or exhibiting position, and means to displace a previously displayed frame to 115 permit another frame to be moved into display position.

3. A display machine, having a storage rack adapted to receive a number of display frames, a transfer rack above the storage 120 rack to receive such frames one by one from the storage rack, a vertically reciprocating carriage provided with means to take the frames one by one from the storage rack and move them to the transfer rack, positively actuated means to transfer the frame on the transfer rack from the rear of the machine to the front and to place it in display or exhibiting position, a shutter carried by the carriage to conceal the frame 130

while being placed in display position, and means to displace the shutter for displaying the frame when so placed.

4. A display machine, having a storage rack adapted to receive a number of display frames, a transfer rack arranged above the storage rack to receive such frames one by one from the storage rack, a vertically reciprocating carriage provided with means to take the frames one by one from the storage rack and move them to the transfer rack, positively actuated means to transfer the frame on said transfer rack from the rear of the machine to the front and to place it in display or exhibiting position, means to displace a displayed frame to permit another frame to be moved into display position, and means to transfer a displaced frame onto the storage rack.

5. A display machine, having a storage rack adapted to receive a number of display frames, means to receive such frames one by one from said rack, a vertically reciprocating carriage provided with means to take the frames one by one from the rack and move them to the frame-receiving means, positively actuated means to transfer the frame from the rear of the machine to the front and to place it in display or exhibiting position, means to displace a displayed frame to permit another frame to be moved into display position, means to transfer a displaced frame onto the storage rack, and means to exert rearward pressure upon the transfer means so as to insure the positioning of the rearmost frame on the rack with relation to the ascending carriage.

6. In a display machine, a vertically reciprocating carriage, a rack provided with a series of display frames arranged in the path of movement of the carriage, means on the carriage to take the frames from the rack one by one and move them to a distant frame support, rock levers adapted to engage the frame on the carriage and move it on said support into display position and retain it in such position for a predetermined time, an intermittently rotating cam shaft, and a rock shaft connected with said rock levers and with said cam shaft to actuate said rock levers.

7. In a display machine, a vertically reciprocating carriage, a stationary rack containing a number of display frames, means on said carriage to take the frames one by one and move them into position for transfer to display position and then recede, means on said carriage to engage a previously displayed frame and return it to the level of the rack, and means to transfer the previously displayed frame from the carriage to the rack.

8. In a display machine, a vertically reciprocating carriage, a stationary rack containing a number of display frames, means

on said carriage to take the frames one by one and move them into position for transfer to display position and then recede, means on said carriage to engage a previously displayed frame and return it to the level of the rack, and means to transfer the previously displayed returned frame from the carriage to the rack, said means comprising rock levers, a shaft on which they are mounted, an intermittently rotating cam shaft, and means interposed between the rock shaft and cam shaft to move and control the rock levers, said rock levers provided with frame-supporting lugs to receive the returned displayed frame from the carriage.

9. In a display machine, a vertically reciprocating carriage, a stationary rack containing a number of display frames, means on said carriage to take the frames one by one and move them into position for transfer to display position and then recede, a shutter for concealing the frame while being moved into position, means on said carriage to engage a previously displayed frame and return it to the level of the rack, and means to transfer the previously displayed returned frame from the carriage to the rack, said means comprising rock levers, a shaft on which they are mounted, an intermittently rotating cam shaft, means interposed between the rock shaft and cam shaft to move and control the rock levers, said rock levers provided with frame-supporting lugs to receive the displayed and returned frame from the carriage, and said rock levers adapted to support the shutter in frame-concealing position for a predetermined time.

10. A display machine, provided with uprights, a storage rack fixed to said uprights and adapted to receive a series of display frames having laterally extended trunnions, a transfer rack likewise fixed to the uprights above the storage rack, a vertically reciprocating carriage traveling on said uprights past the storage rack and slightly beyond the level of the transfer rack and having hooks at its rear to engage the trunnions of the rearmost display frame on the storage rack and in the ascent of the carriage to carry the said frame to the transfer rack.

11. A display machine, provided with uprights, a storage rack fixed to said uprights and adapted to receive a series of display frames having laterally extended trunnions, a transfer rack likewise fixed to the uprights above the storage rack, a vertically reciprocating carriage traveling on said uprights past the storage rack and slightly beyond the level of the transfer rack and having hooks at its rear to engage the trunnions of the rearmost display frame on the storage rack and in the ascent of the carriage to carry the said frame to the transfer rack and deposit it

on said transfer rack, said transfer rack having pendant projections and adjacent spring latches between which the trunnions of the display frame are moved by the carriage onto the transfer rack.

12. A display machine, provided with uprights, a storage rack fixed to said uprights and adapted to receive a series of display frames having laterally extended trunnions, 10 a transfer rack likewise fixed to the uprights above the storage rack, a vertically reciprocating carriage traveling on said uprights past the storage rack and slightly beyond the level of the transfer rack and having hooks 15 at its rear to engage the trunnions of the rearmost display frame on the storage rack and in the ascent of the carriage to carry the said frame to the transfer rack and deposit it on said transfer rack, said transfer 20 rack having pendant projections and adjacent spring latches between which the trunnions of the display frame are moved by the carriage onto the transfer rack, and rock levers pivoted to the uprights above the 25 storage rack and extending upwardly above the transfer rack and having a back-and-forth sweep so as to be positioned back of the said pendant projections and spring latches and consequently behind the trunnions of the ascending frame and thereafter in the cycle of movements to engage 30 said trunnions and transfer the display frame to the front of the transfer rack for exhibition purposes.
13. A display machine, provided with uprights, a storage rack fixed to said uprights and adapted to receive a series of display frames having laterally extended trunnions, a transfer rack likewise fixed to the uprights 40 above the storage rack, a vertically reciprocating carriage traveling on said uprights past the storage rack and slightly beyond the level of the transfer rack and having hooks at its rear to engage the trunnions of the 45 rearmost display frame on the storage rack and in the ascent of the carriage to carry the said frame to the transfer rack and deposit it on said transfer rack, said transfer rack having pendant projections and adjacent 50 spring latches between which the trunnions of the display frame are moved by the carriage onto the transfer rack, and rock levers pivoted to the uprights above the storage rack and extending upwardly above the 55 transfer rack and having a back-and-forth sweep so as to be positioned back of the said pendant projections and spring latches and consequently behind the trunnions of the ascending frame and thereafter in the cycle 60 of movements to engage said trunnions and transfer the display frame to the front of the transfer rack for exhibition purposes, spring cam levers mounted on the transfer rack and extending into the path of movement of the frame being transferred, guards 65

over said cam levers, and levers pivoted to the transfer rack at the front of the machine and engaged by the cam levers and adapted to support the display frame in display position and to release said display frame upon a recurrence of the ascent of the carriage.

14. A display machine, provided with uprights, a storage rack fixed to said uprights and adapted to receive a series of display frames having laterally extended trunnions, 75 a transfer rack likewise fixed to the uprights above the storage rack, a vertically reciprocating carriage traveling on said uprights past the storage rack and slightly beyond the level of the transfer rack and having hooks at its rear to engage the trunnions of the rearmost display frame on the storage rack and in the ascent of the carriage to carry the said frame to the transfer rack and deposit it on said transfer rack, said transfer 80 rack having pendant projections and adjacent spring latches between which the trunnions of the display frame are moved by the carriage onto the transfer rack, and rock levers pivoted to the uprights above the storage rack and extending upwardly above the transfer rack and having a back-and-forth sweep so as to be positioned back of the said pendant projections and spring latches and consequently behind the 85 trunnions of the ascending frame and thereafter in the cycle of movements to engage said trunnions and transfer the display frame to the front of the transfer rack for exhibition purposes, spring cam levers 90 mounted on the transfer rack and extending into the path of movement of the frame being transferred, guards over said cam levers, levers pivoted to the transfer rack at the front of the machine and engaged by the cam levers and adapted to support the display frame in display position and to release said display frame upon a recurrence of the ascent of the carriage, said carriage having hooks at its front onto which the released frame drops and by which upon the descent of the carriage said frame is carried down to the storage rack.
15. A display machine, provided with uprights, a storage rack fixed to said uprights and adapted to receive a series of display frames having laterally extended trunnions, a transfer rack likewise fixed to the uprights above the storage rack, a vertically reciprocating carriage traveling on said uprights past the storage rack and slightly beyond the level of the transfer rack and adapted to take a display frame from the storage rack and elevate it to the transfer rack, means to move the frame to the front of the transfer 115 rack, a trip-lever mechanism at the front of the transfer rack on which the display frame is supported during the exhibiting period, and inwardly projecting lugs on the carriage 120 adapted to trip the said mechanism on the 125 130

ascent of the carriage and thereby release the displayed frame.

16. A display machine, provided with uprights, a storage rack fixed to said uprights 5 and adapted to receive a series of display frames having laterally extended trunnions, a transfer rack likewise fixed to the uprights above the storage rack, a vertically reciprocating carriage traveling on said uprights 10 past the storage rack and slightly beyond the level of the transfer rack and adapted to take a display frame from the storage rack and elevate it to the transfer rack, means to move the frame to the front of the transfer 15 rack, a trip-lever mechanism at the front of the transfer rack on which the display frame

is supported during the exhibiting period, and inwardly projecting lugs on the carriage adapted to trip the said mechanism on the ascent of the carriage and thereby release 20 the displayed frame, and hooks on said carriage on which the thus released frame drops and by which it is carried to the storage rack upon the descent of the carriage.

In testimony whereof I have hereunto set 25 my hand this 24th day of September, A. D. 1920.

OREN F. BALTZLEY.

Witnesses:

RALPH L. BOYER,
